ABSTRACT: An antisplash device for use in conjunction with a douching or rinsing apparatus includes a substantially conical or frustoconical hollow shell member received in an upper opening in a guard ring in the form of a section of a sphere. The inner concave surface of the shield member controls and guides the water issuing from the douching apparatus while the outer surface thereof cooperates with the guard ring to prevent slashing of returning used water and to shield the fresh water from this used water.

PATENTED JUL 6 1971

Fig. 3.

ANTISPLASH DEVICE

FIELD OF THE INVENTION

The present invention relates to an antisplash device for use in conjunction with a douching device to provide protection against stray water issuing from the douching device and, in particular, to an antisplash device which is adapted to be releasably attached to a bidet, toilet seat, bath tub or any other suitable support. The invention further relates to an antisplash device pivotally attached to a seat frame and provided with a holder for a douching or irrigating device, for example, a douching device forming part of a bath tub fixture.

BACKGROUND OF THE INVENTION

Bidets or like devices are used for gentle and effective cleaning of individual body portions, particularly in conjunction with douching or similar rinsing devices for anal irrigation, for medical, therapeutic or purely sanitary cleaning purposes. However, soiling of the room and user by stray water as well as soiling of the douching or rinsing device by the returning used water is a problem which cannot be entirely avoided and is one of particular seriousness regarding stationary bidets, so-called standard bidets, as well as other bidet devices which are not fitted with protective devices guarding against "stray" and/or "spray" water.

It is noted that a device for protection against stray and spray water must not reduce the desired rinsing or cleaning effect, but should contribute to the attainment of a proper cleaning rinse suitable for various purposes or needs. In any satisfactory application whereas the clean water thrown up by the douching or rinsing device must be collected and must be projected at the required spray pressure required, nevertheless it must be possible to adjust the water flow to form a douchelike cluster of jets which has a limited spray pattern, which can be directed or guided in the form of a finely divided spray towards a corresponding treatment point, and which has a locally adjustable effective cleaning or rinsing effect suitable for the treatment in question. Further, the returning used water must not fall back onto the clean water jet or the douching or rinsing device and must not spray about the general area. In brief, bidet devices known heretofore do not fulfill the demands made on such sanitary devices for both hygienic and aesthetic reasons and thus there exists a need for a device which will perform the various functions noted and still be acceptable from both a hygienic and an aesthetic standpoint.

SUMMARY OF THE INVENTION

The disadvantages and defects in prior bidet devices described above as well as others not specifically described are avoided by the antisplash device according to the invention.

In accordance with the invention an antisplash device for use in conjunction with a douching or rinsing device is provided which comprises a guard ring in the shape of a hollow ball or hemispherical shell, and a hollow shield member of substantially conical or frustoconical shape, the guard ring having an open base adapted to receive therein a douching or rinsing device, and an opening in the apex in which the shield member is attached to the guard ring, the shield member having an open base which faces the douching or rinsing device when the latter is in position, and at least one opening in the top of the shield member to serve as an outlet for water issuing from the douching or rinsing device.

Preferably the antisplash device is adapted to be attached to a seat frame of a bidet, toilet, bath tub or other support.

The invention extends also to an antisplash device as defined above, wherein the device is attached to a seat frame and incorporates a holder for a douching or rinsing device or a holder with a douching or rinsing device, the seat frame being part of, or attachable to, a bidet, toilet, bath tub or other support.

The concave inner surface of the guard ring facing the douching or rinsing device is intended to catch douching water or clean water travelling beyond the limits of the area of the opening is open of the guard ring, and the convex outer surface thereof facing the seat frame or the treatment point is intended to catch returning used water and guide it past the douching or rinsing device in a splash-free manner. The conical or frustoconical control or shield member attached to the open opening of the guard ring, being open at its base facing the douching or rinsing device will catch any clean water which travels upwardly through the base opening in an undesirable lateral direction, and thus will prevent clean water from spraying about during its passage through the conical shield member. The opening or openings in the top of the shield member guide or direct the clean water towards the treatment point in the form of a single jet, a cluster of jets or a finely distributed spray which has a limited spray pattern. Means may be provided for adjustment of the positioning of the device to the respective needs of a user and for directing the flow of water towards the treatment point. The antisplash device thus produced may be carried together with the douching or rinsing device by a composite holder which may be pivotally attached to a seat frame forming part of, or attachable to a bidet, toilet, bath tub or other support.

BRIEF DESCRIPTION OF THE DRAWINGS

One embodiment of the invention will be described below by way of example with reference to the accompanying drawings, in which:

FIG. 1 is a side elevational view of a diagrammatical representation of an antisplash device in accordance with a presently preferred embodiment of the invention;

FIG. 2 is a top elevational view of the device of FIG. 1, and

FIG. 3 is a diagrammatic perspective view of the device of FIGS. 1 and 2 attached to the seat frame of a bidet.

DESCRIPTION OF A PREFERRED EMBODIMENT

An antisplash device according to the invention consists of a guard ring 1 and a control or shielding member 3 attached thereto and forming with the guard ring a unit serving as protection against stray and spray water. The guard ring 1 has approximately the shape of a section of a hollow sphere or hemispherical shell having a lower opening or open base 2 and an apex opening 5. A control or shield member 3 is attached to the apex opening 5, the shield member 3 having the shape of a truncated cone and being provided with an opening 4 at the base thereof facing towards a douching or rinsing device 10 (FIG. 3), and with an opening 6 at its top facing towards a seat frame 8 or the treatment point. If desired, a plurality of openings 6 may be provided. The conical shield member 3 may be attached to the guard ring 1 in such a manner that the base opening 4 of the shield member 3 coincides with the open opening 5; alternatively the base opening 4 may be offset downwardly to some extent below the peripheral edge of the apex opening 5 as indicated by a broken line in FIG. 1. However, the opening 5 should surround the conical outer wall of the control or shield member 3 tightly regardless of the longitudinal position thereof relative to the base opening 4.

The inner concave surface of the guard ring 1 is intended to catch clean water which travels upwardly from the douching or rinsing device 10 beyond the limits of the open opening 4, the douching or rinsing device being disposed below the antisplash device so that undesirable scattering of water is effectively avoided, whereas the convex outer surface has the task to intercept returning used water and to guide it in a substantially splash-free manner past the clean water jet or jets and the douching or rinsing device 10 and over the peripheral edge of the guard ring 1 to an outlet, a return water collector or the like (not shown).

The conical shield member 3 attached to the apex opening 5 serves the purpose of catching the clean water travelling upwardly through the base opening 4 and of controlling and guiding this water through apex opening 6 in a spray-free

manner to the treatment point in the form of a cluster of jets constituting a finely divided but coherent clean water spray of a controlled spray pattern, adjustable to the particular needs of a user.

The guard ring 1 contains a plurality of peripheral recesses and perforations 7. The antisplash device 1, 3 and the douching or rinsing device 10 are supported by a holder 9 which consists of a plurality of parts and which engages supportingly into the peripheral recesses 7 of the guard ring 1. Portions of the holder 9 is preferably angled with respect to antisplash device 1, 3 and the holder 9 is provided with a number of carrier members 11, located at an angle with respect to the plane of the guard ring 1, for mounting the douching or rinsing device 10, the position of the carrier members 11 being adjustable. As is illustrated schematically in FIG. 3, the holder 9 is pivotally and removably attached to the seat frame 8. The device according to the invention permits a clean waterflow to be obtained which does not splash or stray and which can be adjusted in accordance with the needs of various application purposes. Further, the flow is substantially centered and guided so that spraying of the water and the resulting soiling are precluded and hence the formation of colonies of bacteria and the transfer of various illnesses is avoided. At the same time, the sanitary cleaning provided by the present invention is effective and gentle. A unit incorporating the antisplash device according to the invention together with a seat frame, to which the device may be attached by a holder which is adapted to receive a douching device, or which is provided with a nozzle ready for connection to a water supply is readily transportable and can be stored for immediate use. The device, or the whole unit, may be used ambulatorily and may be employed, for example, in hospitals, private dwellings or convalescent homes with limited toilet or bathroom space.

Although the invention has been described in detail with particular reference to preferred embodiments thereof, it will be understood that variations and modifications can be effected within the scope and spirit of the invention as described hereinabove and as defined in the appended claims.

I claim:

1. An antisplash apparatus for use with a douching or

rinsing device, comprising an antisplash device comprising a guard ring in the shape of a section of a hollow spherical shell, and a hollow shield member of substantially conical or frustoconical shape defining a duct for the passage of water

5 therethrough, said guard ring having an open base for catching douching water or clean water from a douching or rinsing device of a bidet, toilet or other support, and an opening in the apex thereof which the shield member is received, said shield member having an open base which faces the douching or 10 rinsing device when the latter is in position, and at least one opening in the top of the shield member for providing an outlet for water issuing from the douching or rinsing device and flowing through the duct defined by the a shield member.

2. An apparatus as claimed in claim 1, further comprising 15 means for attaching said antisplash device to a seat frame of a bidet, toilet, bath tub or other support.

3. An apparatus as claimed in claim 1 further comprising means for attaching the shield member to the guard ring in such a manner that the open base of the shield member coincides with the apex opening of the guard ring.

4. An apparatus as claimed in claim 1 further comprising means for attaching the shield member to the guard ring in such a manner that the open base of the shield member is located below the peripheral edge of the apex opening of the 20 guard ring, the edge closely surrounding the shield member.

5. An apparatus as claimed in claim 1, further comprising a holder for pivotally and removably attaching said antisplash device to a seat frame of a bidet, toilet, bath tub or other support, said holder including means for supporting a douching 30 device or nozzle and including carrier members and mounting members located at an angle to the plane of the guard ring and adjustable relatively thereto.

6. An apparatus as claimed in claim 5, wherein the holder is 35 removably attached to the support device of a bidet.

7. An apparatus as claimed in claim 5, wherein the holder engages supportingly into peripheral recesses in the guard ring by means of a member which is approximately parallel to the base area of the guard ring and embraces, in a position securing manner, a part of the peripheral edge of the guard ring at a 40 location approximately diametrically opposite the recesses.
